UNITED STATES PATENT OFFICE.

FRIEDRICH MERK, OF BERLIN, GERMANY

AUTOMATIC TELEPHONE SYSTEM.

No. 853,818.

Specification of Letters Patent.

Patented May 14, 1907.

Application filed January 2, 1907. Serial No. 350,386.

To all whom it may concern:

Be it known that I, FRIEDRICH MERK, telephone engineer, a citizen of the German Empire, residing at Flottwellstrasse 7, Berlin, 5 Germany, have invented certain new and useful Improvements for Automatic Telephone Systems, of which the following is a specification.

In automatic telephone exchanges from 10 about 100 subscribers upward it is customary to arrange in groups the subscribers' lines in the exchange, and to make connections from one subscriber to the other or from one group to the other by the aid of trunk-lines. The 15 subdivision of the exchanges in groups and the use of trunk-lines is generally extended the more, so much the larger the number of the subscribers' lines is. In quite large exchanges main-groups, sub-groups and by- 20 groups etc. are distinguished, whereat the completion of connections is brought about, so to say, step by step in such a manner that the complete talking circuit passes from the calling subscriber to the called one over a 25 number of trunk-lines through the desired main-group, sub-group, by-group etc.

The grouping system widest known and 30 most developed, to which also the present invention refers, is the Strowger system in which the characteristic difference from other 35 systems and the advantage over them consist in the fact that the grouping of the subscribers is based on the decimal system, whereat a 100-, 1000-, 10000- etc. system are 40 distinguished and in which the number of the trunk-lines between the groups and the switches connected thereto is reduced so uniformly that the number of switches, from the second stage of switching, corresponds approximately to the number of connections to 45 be made simultaneously. This latter result is attained by reason of the fact that the trunk lines, at all stages of the switching, are connected in multiple to the corresponding 50 selectors, which is a distinguishing feature of my system.

In the arrangement of groups according to the decimal system mentioned, subscribers' sub-groups are chosen as units and thus the 55 switches for each 100 subscribers are joined on one switchboard. The number of switches for each switchboard is a little larger in the 1000-system than in the 100-system and again a little larger in the 10000-system than in the 1000-system. This increase is caused

by the circumstance that, when changing from one system to the other, one switch and one trunk-line more is necessary for every single connection. The number of trunk lines per connection in the 100-system is = 0, 60 that is the subscribers' lines are directly connected; in the 1000-system it is = 1, in the 10000-system = 2 etc. Thus the number of switches necessary per connection in the 100-system is = 1, in the 1000-system = 2, in the 65 10000-system = 3 etc. In order, now, to overlook the total number of switches which, in the case of the present invention, cuts a figure, in the following the combination of a single switchboard for the different kinds of 70 systems is given.

In the 100-system one switchboard contained till now: 100 connectors. In the 1000-system one switchboard contained till now: 100 selectors and 10 connectors in all 75 110 switches. In the 10000-system one switchboard contained till now: 100 first selectors, 10 second selectors and 10 connectors in all 120 switches. These values are valid in the 100- and 10000-system under the 80 position that in every calling direction ten percent of trunk-lines are provided. In a higher percentage of trunk-lines, however, the total number of switches increases but comparatively little. 85

A well known disadvantage of the system just characterized is that in the first switching stage there exists a disproportionate large expenditure of switches. This expenditure is much larger than is necessary for the talking traffic. For, since for every connection there is but one switch necessary of each kind of switches (first, second etc. selector and connector), in reality all kinds of switches in the exchange ought to be of the same number. If 90 till now, nevertheless, for the first switching stage ninety percent more switches have been used than for the following stages, this is simply due to the circumstance that it was not at all an easy matter to reduce the number of first selectors. Naturally, however, it must be the endeavor of technology to do away with this inconvenience. Among the 95 different possibilities offering themselves for the said purpose, that one will have the precedence that provides, for all stages of switching, the same number of switches. This aim at an equal reduction of all kinds of switches (first, second etc. selectors and connectors) is attained, in the present invention, by means 100 105 110

of a combination of the so-called double-switch principle with the group arrangement of the Strowger system.

By the expression "double-switch principle" a method of switching is characterized which presents itself as a transferring of the double-cord system customary in manual exchanges. The double-cord system is known to be based on the application of short cords

which are at both ends provided with plugs (answering and calling plugs), and which are applied by the operator in such a way that, when making a connection, she inserts the answering plug in the jack of the calling subscriber's line and the calling plug in the jack of the desired line (subscriber's or trunk-line).

The number of cords or pairs of plugs is so proportioned for every operator's place that, in the time of the heaviest traffic, all desired connections can be made. Generally for 100 subscribers' lines 10 to 15 pairs of plugs are sufficient.—When this principle is transferred to automatic telephone exchanges, the pairs of plugs are replaced by pairs of switches, the

movable contacts of which—corresponding to the plugs of a cord—are joined. When a connection is made, one switch, the so-called preselector, is set on the line of the calling subscriber, and the second switch belonging thereto, a normal selector or connector, is set on the line to be called. As, for every connection, one pair of switches is necessary, it is sufficient, according to the experience with the double-cord system, to have about 10 to

15 pairs of switches for 100 subscribers' lines. Now, the combination of the double-switch principle with the Strowger grouping method outlined above, is carried out in such a manner that, for every desired connection with

another subscriber, the connection from the calling subscriber's line to the next trunk-line is made with pairs of switches (preselectors and first selectors), whereas the further connections from the first to the second and to every following trunk-line as well as to the line of the desired subscriber are, as hitherto, made in the manner of the single-cord operation also customary in manual exchanges, that is by single switches, at the same time basing this method on the well-known Strowger grouping system.

The simplification resulting herefrom for a switchboard of the improved Strowger type is outlined in Figure 1 of the annexed drawings. Accordingly, a switchboard for 100 subscribers comprehends, under consideration of ten percent of simultaneous possibilities of connections: in the 100-system, 10 pre-selectors and 10 connectors in all 20 switches; in the 1000-system, 10 pre-selectors, 10 selectors and 10 connectors in all 30 switches; in the 10000-system, Fig. 1, 10 pre-selectors, 10 first selectors, 10 second selectors and 10 connectors in all 40 switches. To this are added, in every instance, 100 calling and cut-off re-

lays, 10 little lamps and one simple group-switch arranged laterally in a small box. As the last-mentioned arrangements are in value as high as about 10 switches, the saving, as compared with the above systems hitherto in use, amounts to:

In the 100-system 100-20-10
In the 1000-system 110-30-10
In the 10000-system 120-40-10 = 70 switches per 100 subscribers.

Together with this considerable saving of apparatus, which is the same in exchanges of any size, the following advantages are at hand:

1. The switchboards together with relays and group-switch are reduced to more than one half of their former size, and they can be packed, transported and mounted without being taken apart. The size of an exchange is thus reduced to more than one half.

2. The survey over the single switchboards is better, all the single kinds of switches being represented in equally reduced numbers.

3. The percentage of possible connections can be increased, for all switching stages, to any desired capacity by simply adding new switches, provided the switchboards are kept a little broader from the beginning.

4. In every switchboard the whole supply of preselectors and first selectors is equally at the disposal of every one of the 100 subscribers connected thereto.

Among all the methods of switch-reducing for automatic telephone exchanges hitherto known there is not one that combines so many advantages as the one above-mentioned. In one older system, f. i., although the individual switches are simplified, their number is not reduced but even increased, as, to the simplified individual switches ten to fifteen percent first selectors have to be added. In another system the subscribers are connected to relays for switching their lines on common first selectors, but with such an accumulation of these relays combined with such a limitation of the possibility of getting connections that this invention seems to be of but doubtful value. In a third system, at last, the reduction of first selectors is carried out, as in the present invention, by the addition of preselectors, but not in combination with the Strowger grouping method. This departure shows itself disadvantageously in the fact that the number of second selectors rises in an extraordinary manner with the increasing size of the exchanges, so that to a certain degree the switches saved in the first stage of switching have to be expended again in the second one.

Example of Construction of the Invention.

As an example a Strowger 10000-system is taken, in which the first and second selectors as well as the connectors are provided in the well-known normal construction, whereas the subscribers' apparatus differ to a small

extent from the normal. The difference, as compared with the former construction of the system, is to be found in the fact that in every switchboard from the 100 first selectors necessary until now about 90 selectors are saved, whereas about 10 preselectors, 100 calling and cut-off relays and a simple group-switch are added, so that the switchboards now take the form of the Fig. 1 already mentioned. The single parts are explained in the following by the aid of the drawings and with reference to construction and effect. Their new features are minutely explained, whereas all the former constructions are but outlined.

In the drawing is shown by Fig. 1 a switchboard such as is employed in connection with my invention. Figs. 2 and 3 two subscribers' telephones No. 1523 and No. 1538; Fig. 4 the calling and cut-off relays in the exchange belonging thereto; Fig. 5 the sources of current in the exchange; Fig. 6 the group-switch of the 100-group to which the two telephones above-mentioned belong; Fig. 7 a preselector; Fig. 8 a first selector; Fig. 9 a second selector and Fig. 10 a connector.

A. Equipments.

1) *Subscriber's apparatus.* Fig. 2 is the wiring diagram of the apparatus and Fig. 3 shows the telephone in its outward appearance. Besides a receiver, a microphone with battery, an induction coil, a movable arm for the receiver and an alternate current ringer, every telephone is equipped with a calling device characteristic to the Strowger system and with a ringing button *d*. The calling device consists of a round dial *n* rotatory around its axle, behind which is the device for sending impulses over the line. The dial is provided with 10 finger holes numbered 1, 2, 3 . . . 9, 0. When the telephone is to be used f. i. to call the number 1538, the receiver must be taken down and the dial be turned in a downward direction in succession from the numbers 1, 5, 3 and 8, and after each turn the dial must revolve to its normal position. Every time the dial returns to normal again, the impulse-sending device sends, in a manner to be described later on, successively 1, 5, 3 and 8 impulses over the *a*-branch of the line and, following each return of the dial, one impulse goes to the exchange over the *b*-branch. These impulses operate, correspondingly, the switches in the exchange, and thus the connection to the desired subscriber is completed. After the last turning of the dial the button *d* is to be pressed down, by which manipulation the *a*-line is grounded again and the bell of the desired subscriber rings. If, after a connection, the receiver is hanged on again, the downward moving receiver arm closes an impulse over *a* and *b* by which impulse the connection is severed again in the exchange.

The apparatus is similar to the Strowger telephone in all these details. A new feature is a condenser which, when the receiver is on its hook, is inserted between the *a*- and *b*-line together with the ringer in order to block the common battery *F* (Fig. 5) which is inserted, when idle, between the *a*- and *b*-line. Besides that contact *u* which, when the dial is turned, interrupts the connection between the *a*- and *b*-line, is mechanically so altered that *a* and *b* are only disconnected while the dial returns to its normal, but not, as till now, also when it is turned down.

2) *Calling and cut-off relays.* As per Fig. 4, every subscriber has, in the exchange, a calling relay *R'*, *R''* and a cut-off relay *T'*, *T''*, each of them provided with two contact springs. When the subscriber's line is at normal, the calling relay is inserted, over the interrupting contacts of the cut-off relay and the interrupting contact *e*² in Fig. 6, together with the battery *F*, between the *a*- and *b*-branch of the subscriber's line belonging thereto. If, therefore, a subscriber connected to a line which is at normal takes down his receiver, the respective calling relay in the exchange is energized. The cut-off relay which is generally on the busy line *c'*, *c''* over one of the resting contacts of the calling relay, cuts off, after the setting on a subscriber's line of one of the preselectors or selectors, the corresponding calling relay. In the drawing the two cut-off relays *T'* and *T''* are energized, as it is presumed that a connection exists between the subscribers Nos. 1523 and 1538.

In the drawing are represented, below the calling and cut-off relays, 10 main conductors 1, 2, 3 . . . 9, 0 to which a branch is leading from every calling relay. The connection of these branches depends upon the tens of the number of the respective subscriber. The branch from relay *R'*, f. i., leads to the main conductor 2, the corresponding subscriber belonging to the second group of tens, whereas the branch from relay *R''* which belongs to a subscriber of the third tens group leads to main conductor 3. On the left in Fig. 4 the main conductors pass through lamps, among them *x*², and are then joined in one point, whence they go over line 6' and the relay *R* in Fig. 6 to the - pole of the battery *F*. When a calling relay, f. i. *R'*, responds, a current flows on the stroke-dotted line over the relay *R* and the lamps *x*². The lamps have, as may be seen later on, the effect of compensation resistances. Besides they show, at the same time, from which group of tens a call has been made.

The calling and cut-off relays are, as per Fig. 1, arranged in a special frame, in 10 horizontal rows of 10 pieces each, on the switchboards below the switches. On the left side of every row of relays is provided the lamp belonging thereto.

3) *Sources of current.* Fig. 5 represents the source of current in the exchange. F is the normal working battery grounded with its - pole, V is a small subsidiary battery, C an alternate current generator for ringing and for the busy signal. U is a rotatory interrupter for generating impulses from direct current.

4) *Group-switch, Fig. 6.* This apparatus is provided but once for every 100-group, i. e. for each switchboard, and consists of four relays R, K, Z, E; one so-called tens-finder ZS and one so-called selector-finder WS.

15 The apparatus are placed, as mentioned before with reference to the Fig. 1, in a small box protecting them when being transported and in the course of operation and making a quick replacing possible.

20 The group-switch has the purpose, when a calling relay responds, that is when a receiver is taken from the hook, to set on the calling subscriber's line perfectly automatically and in the quickest manner possible, by the aid of the interrupter U an idle preselector, thus connecting the calling subscriber to a first selector. While the preselector remains then connected to the calling subscriber until the receiver is hanged 25 on the hook, the group-switch is free again immediately and at disposal for other calls.

30 In order to explain the signification of the single parts of the group-switch, the manner of operation of the preselectors is outlined 35 in the following.

35 As soon as a subscriber has the intention to make a call and takes the receiver from the hook, the next idle preselector on turn in the exchange leaps out of its normal position and sets on the calling subscriber's line which is connected to one of the 100 fixed contacts of the switch, same as in the case of the Strowger switches, by a vertical and a horizontal motion of the rod. The setting 40 on line of the preselector corresponds, as compared to manual operation, to the inserting of a free answering-plug in the jack of the calling subscriber's line by the operator. The performance of the operator is effected, in the present automatic system, 45 by the group-switch. The group-switch receives every call out of the respective group, it appoints the preselector to be used, it starts the rod and limits its vertical and horizontal motions to the necessary extent. The group switch governs, so to say, the preselectors, the interrupter U and the battery F giving the energy, while the calling subscriber, by simply taking off its receiver, 50 starts the whole operation of the preselector. This general characteristic of operation of the preselectors given, the essence of the single parts of the group-switch ought to be easily intelligible.

55 Relay R is the common calling relay, which

responds every time a subscriber's calling relay is energized. It prepares, by the aid of the group-switch, the coupling of an idle preselector.

60 Relay K is the starting relay which, when being energized, makes the rod of the coupled preselector rise by closing impulses of the interrupter U. The same impulses flow, at the same time, through the tens-finder ZS explained later on which rotates synchronous 7 to the preselector in order to find out, by testing the single main conductors 1, 2, 3 . . . 9, 0, the calling tens-group and to reduce the impulses effective when the rod is lifted to the necessary extent.

65 Relay Z is the tens-relay which responds as soon as the tens-finder ZS has found the calling tens-group, and which then switches the impulses of the interrupter U from the lifting magnet of the preselector to the 8 turning magnet, so as to make the preselector commence to rotate.

70 Relay E is the units- or disconnecting relay which responds in the case of a preselector arriving on the calling subscriber's 9 line, and which stops the preselector and disengages the group-switch. This relay has a low resistance for the reason which will appear hereinafter.

75 The tens-finder ZS accompanies synchronously every preselector when the rod rises, in order to find out, as mentioned, the calling tens-group and to stop, at the due moment, the rising preselector. The apparatus is a rotating switch with ten fixed contacts to 10 which the main conductors 1, 2, 3 . . . 9, 0 mentioned before are connected successively, and over which the contact-arm *i* slides. The arm *i* is pulled upward by a spring (not represented in the drawings) so that, when at normal, it takes the position shown in the drawing, keeping open the short-circuit contact *i* for the common calling relay R. The arm *i* rotates when impulses pass the electromagnet J and move to and fro the pawl engaging 11 in the toothed wheel while, at the same time, a constant current passes the solenoid J'. The arm *i* moves, with every impulse passing J, from one contact of the main conductor to the next one. As soon as the solenoid 12 J is without current again the arm *i*, under the effect of the above-mentioned spring, returns immediately to its normal position.

80 The selector-finder WS selects an idle preselector in the case of a call. This apparatus is also a rotating switch, however, with a contact-arm *w* always rotating in the same direction, and with so many fixed contacts arranged in a circle as may be necessary for 100 subscribers in the case of the heaviest 13 possible traffic. As a rule, 10 to 15 contacts come in question. The electromagnet W, whenever it has been excited, switches the arm *w* from one fixed contact over to the 14 next one. To these contacts lines I, II, III 15

etc. are connected, each of them leading to another preselector. Line I, *f. i.*, leads to the preselector Fig. 9. When a subscriber calls, he is connected to that preselector on the lines I, II etc. of which the arm *w* rests at that moment. Even during the act of setting the preselector on line the arm *w* rotates immediately to the line leading to the next preselector. If this apparatus is in operation, the arm continues to move until it finds an idle preselector. The selector-finder, as mentioned before, — during the act of setting on line the preselector just engaged — immediately moving on to the next idle preselector, another preselector will always be found before the connection prepared is completed, so that no time whatever is lost by finding an idle selector. A remarkable feature is to be found in the fact that all the preselectors (and, simultaneously, all the first selectors) are employed in regular cyclic sequence.

5) *Switches.* The Figs. 7 to 10 represent the switches coming in operation in the course of the connection between the subscriber No. 1523 and 1538. Fig. 7 represents a preselector, Fig. 8 shows a first selector, Fig. 9 a second selector and Fig. 10 a connector. The construction of these four switches is standard for all other switches in the exchange. Thus all preselectors are similar to Fig. 7, all first selectors similar to Fig. 8, all second selectors similar to Fig. 9 and all connectors similar to Fig. 10.

The switches, the construction of which corresponds to that of the well-known Strowger switches are all provided with a vertically and horizontally movable contact-arm with three contacts each. The latter can be connected by the movable contact-arm to the contacts of 100 triple lines *a*, *b*, *c* firmly arranged in ten rows of ten times three contacts each. The setting on contacts of the arm is effected step by step by means of the electromagnets *H* and *D*. *H* lifts, whenever it is energized, the contact-arm from one row of contacts to the next one. *D* rotates the arm over the selected row of contacts. The contact-arm is so arranged as to be lifted two steps and rotated three steps for a connection to No. 23, and lifted three steps and rotated eight steps for a connection to No. 38.

The selectors Figs. 8 and 9 and the connector Fig. 10 have, as compared with the comparatively simpler preselector, Fig. 7, the following common features: in the first place a relay *A* and *B* for transferring the impulses coming from the subscribers' telephones on the local circuits in the switches; secondly a quadruple lever switch *e*, *i*, *o*, *u* for three positions each, for varying the switch circuits during operation. The lever switches are so governed by the electromagnets *S* and *M* that at first the so-called busy magnet *S*, after the first responding, allows the levers *e*, *i*, *o*, *u* which are under the tension of a spring

to leap from their normal position, as given by a stroked line in the drawing, to the middle position and thence, after the magnet has responded again, to the third full-drawn position, whereas the so-called release-magnet *M*, after having responded for a short moment, pulls back the levers and disengages at the same instant the contact arm, as indicated by Fig. 7, by stopping the blocking, so as to allow the contact-arm to return, partially by the effect of a spring and partially by its gravitation, in the well-known manner to its normal position.

The preselector Fig. 7 is specially provided with a coupling-relay *G* which is excited during the time a connection is completed by a preselector, and which, by means of three levers *g*¹, *g*², *g*³ lays on the lines 41, 42, 43 leading to the group-switch Fig. 8 the electromagnets *G*, *D* and *H*.

The connector Fig. 10 contains, specially, the ringing and busy relay *L* and two each of small and large condensers *p*^a, *p*^b and *q*^a, *q*^b respectively. Finally there are to be mentioned, with reference to the switches Figs. 7 and 9, contacts connected to the springs *f* which are pressed down by the contact arm belonging thereto in its normal position, which, however, immediately turn upward as soon as the arm rises.

Each preselector is connected to the corresponding first selector by five direct lines *a*^o, *b*^o, 44, 45 and 46. Of these the full-drawn lines *a*^o, *b*^o lead from the contact-arm of the preselector over the levers *e*¹, *i*¹ to the contact-arm of the first selector. Line 45 connects relay *A*¹ over the lever *g*² and, similar, line 44 connects the relay *B*¹ over the lever *g*¹ to +F. Line 46 connects the release-magnet *M* of the preselector parallel to the release-magnet *M*¹ of the first selector. The five trunk-lines are comparatively short, the two switches in Figs. 7 and 8 and, similar, all the other preselectors and first selectors are arranged in pairs one above the other on the switchboards.

From contact 17 of the first selector a first trunk-line *a*¹, *b*¹, *c*¹ leads to the second selector Fig. 9. In a similar manner a second trunk-line *a*^{II}, *b*^{II}, *c*^{II} leads from contact 57 to the connector Fig. 10. The contacts 17 and 57 are singled out of the contact-rows represented in the drawing for the reason that it is presumed that the lines leaving the contacts 11 to 16 and 51 to 56 respectively are already blocked in other switches where they are connected in a similar manner. Of the further arrangement of these and the other trunk-lines as well as of the position and the arrangement of the selectors and connectors to the trunk-lines, the numerous Strowger exchanges and the descriptions existing thereof (as *f. i.* in the "Elektrotechnische Zeitschrift," Berlin 1903, page 724 to 734, Fig. 57, and page 930, Fig. 40) are re-

ferred to in explanation, so that a detailed explanation of this part of the Sirowger system is not necessary, especially as all that is mentioned here is sufficient to explain the 5 wiring diagrams.

The switches Figs. 7 to 10 having reached the positions shown in the drawing, as will be explained in particulars later on, subscriber No. 1523 is connected to 1538. The talking 10 circuit goes from Fig. 2 along the arrows drawn over the calling subscriber's line a' , b' —contact-arm of the preselector—short line a^o , b^o —levers e^1 , i^1 —contact arm of the first selector, first trunk line a^1 , b^1 , levers e^2 , i^2 , 15 contact-arm of the second selector—second trunk-line a^n , b^n —condensers q^a , q^b —relay levers l^1 , l^2 —levers e^3 , i^3 —contact-arm of the connector—desired subscriber's line a'' , b'' to Fig. 3. The drawing clearly expresses, by 20 the heavy lines, how the connections on the first stage of switching, that is between the calling subscriber's line a' , b' and the first trunk-line a^1 , b^1 , are made similar as in double-cord operation by pairs of switches, 25 whereas on the following switching stages, that is between the first trunk-line a^1 , b^1 and the second trunk-line a^n , b^n same as between the second trunk-line a^n , b^n and the desired subscriber's line a'' , b'' are made similar as in single-cord operation, that is by single 30 switches.

B. Method of Operation.

Supposing that subscriber No. 1523 (Fig. 35 2) wishes to be connected to subscriber No. 1538 (Fig. 3). All of the apparatus represented are at normal. The arm of the selector-finder w (Fig. 6) rests on line I so that, at the next call, the preselector shown in Fig. 7 40 comes to operation.

1) The Setting on Line of the Preselector in Fig. 7.

This setting on line commences immediately and is entirely automatic from the beginning to the end as soon as the subscriber (Fig. 2) has taken the receiver from the hook.

In order to give a better survey, the stages 50 of operation are described in the following in five paragraphs (a to e).

a) The Calling of the Subscriber in Fig. 2 and the Blocking of His Line a' , b' in the Exchange.

When the receiver Fig. 2 is taken down, the alternate current ringer, being between a' and b' together with the condenser, is switched out whereafter a calling current 60 begins to flow in a' and b' .

Line calling circuit: + F (Fig. 5), contact e^2 (Fig. 6), line 4', calling relay R' , resting contact t^1 (T^1 is not excited yet), line a' , telephone in Fig. 2, line b' , resting contact t^0 , line

2'—F. The calling relay R' responds, cuts off the relay T^1 from c^1 by means of the contact spring r^1 and connects c^1 over the working contact r' , line 1', the disconnecting relay E, line 7' and subsidiary battery V to —F. By this circuit in the first place the line a' , b' of the calling subscriber is blocked for other subscribers because conductor c' is connected to the ground over the low resistance relay E and battery V. Then the circuit for the subsequent disconnection of the preselector 75 is prepared in consequence of the connection of relay E to the line c' . Besides relay R' closes, by the spring r^2 , a local circuit over the common calling relay R, as will now be described.

Local calling circuit (stroke-dotted): + F, line 3', contact r^2 , main conductor 2, lamp x^2 , line 6', common calling relay R, —F.

b) The Coupling of the Preselector.

The common calling relay R responds and prepares, by closing the contact r , the coupling of the preselector in Fig. 7. The coupling is effected by the aid of the next current impulse closed by the interrupter U.

Preparatory coupling circuit: + F, coupling relay G (Fig. 7), lower contact of spring f^1 (the switch-rod is still at normal), line I, arm of selector-finder w (Fig. 6), closed contact r and k^1 (Fig. 6), interrupter U, —F. Coupling relay G responds and attracts the three armature levers g^1 , g^2 , g^3 . By g^1 the relay G is connected to line 41, and thus the coupling and locking current mentioned hereafter is prepared; by g^2 the lifting magnet H is connected to line 42 and, in a similar manner, by g^3 the turning magnet D is connected to line 43. H and D, however, receive no current as yet. After relay G has responded and as soon as the current is interrupted at U, the coupling and locking current mentioned before is brought about.

Coupling and locking circuit: + F, relay G (Fig. 7), lever g^1 , line 41, solenoid J' (Fig. 6), common coupling relay K, resting contact e^1 , —F. This current keeps G, as prepared before, excited, while J' and K are also excited and, together with G, are kept so until the preselector is definitely set on line. At the same time the common calling relay R closes, independently of the coupling current, a circuit through working magnet W of the selector-finder, so that arm w moves on already in the next pause made by the current in the interrupter from line I to line H and thus prepares the preselector connected thereto for the next call.

Current impulse for the selector-finder: + F, lower contact of spring f^2 of all preselectors in normal position, line (+), working magnet W and thence together with the preparatory coupling current to contact r and k^1 , interrupter U, —F.

c) *The Setting of the Preselector in the Vertical Direction.*

After relay K has responded the interrupter U sends current impulses through the lifting magnet H and the working magnet J.

Working impulses over H and J: +F, lever g^2 , lifting magnet H, line 42, working magnet J, contact k^2 and z , interrupter U, -F. The current impulses lift the rod of the preselector and turn, synchronously, arm i of the tens-finder. The synchronous working of the two apparatus is insured by the fact that, in the first place, the two co-operating magnets H and J are always switched in in a pause of current in the interrupter by the relay K and, in the second place, that H and J work in series connection, J having but easy work to do. Before the further operation of the preselector and the tens-finder can be followed up, the following by-operations are also to be taken into consideration. The common relay K interrupts, when being at work, at k^1 the way of the preparatory coupling circuit. This way is interrupted again, later on, at r , the relay R being cut out at v by a short circuit after the first working of J. By this opening of the contacts at k^1 and r it is effected that, at every call, only one preselector operates and that other preselectors can in no way be influenced before the tens-finder has returned to its normal position. With the first impulse through the lifting magnet H the springs f^1 and f^2 move in an upward position. In consequence of the opening of the lower contact of f^1 being effected at this moment, relay J is cut off from line I, so that the preselector of Fig. 7, until it returns to normal position, cannot be coupled again. By the closing of the upper contact of f^1 line I is connected to the interrupter U which causes the arm w of the selector-finder, whenever it touches line I again before the releasing of the preselector, not to remain on this line but to immediately be turned on the next line II by the interrupter U. If the preselector of this line is also busy, arm w moves on again until it finds the line to a preselector that is not busy. In order not to let the arm w turn without necessity when all of the preselectors are busy the working magnet W is not fed immediately by +F, but over a line (+) which has connection to +F over the preselector contacts arranged in parallel only so long, as at least one preselector is at normal. The current impulses of the interrupter U through the lifting magnet H and the working magnet J have continued meanwhile. Thus the second impulse has set the contact-arm of the preselector in height of the contact row containing the subscribers' lines 21, 22 . . . and, simultaneously, the arm i of the tens-finder has been placed on the main conductor 2 which, as will be remembered, is connected to +F since the call of the sub-

scriber No. 1523 over the working contact r^2 and the line $3'$.

d) *The Setting of the Preselector in the Horizontal Direction.*

When the arm i touches the main conductor 2, the tens-relay Z is energized.

Circuit over the tens-relay Z: +F, line $3'$, working contact r^2 , main conductor 2, arm i , relay Z, -F. The tens-relay Z, by turning over the contact spring z , cuts the lifting magnet H and the working magnet J out of the interrupter circuit and inserts the turning magnet therein instead.

Working impulses over D: +F, lever g^3 , turning magnet D, line 43, working contact z , interrupter U, -F. The impulses rotate the contact arm of the preselector until, when D is energized the third time, it reaches the contacts 23 of the calling subscriber's line a' , b' , c' .

e) *The Disconnection of the Preselector and the Disengaging of the Group-Switch.*

When the contact-arm of the preselector arrives on line a' , b' , c' , the units or disconnecting relay E (Fig. 5) responds.

Circuit over the units or disconnecting relay E: -V, line 7', relay E, line 1', working contact r^1 , line c' , contact-arm of the preselector, +V. By opening the contact at e^1 , the coupling and locking current is interrupted so as to make G, J' and K simultaneously currentless. By G the preselector in Fig. 7 is cut off from the common lines 41, 42 and 43, while J' causes the arm i of the tens-finder to return to its normal position. By opening the contact at e^2 the line calling circuit is interrupted, and thus relay R' is made currentless. The resting contact then closing at r^1 , relay T' is connected to line c' and immediately energized by the preselector.

Cut-off current over T': -F, contact-arm of the preselector, line c' , resting contact r^1 , relay T', line 5' and 3', +F. By the fact that T' is excited, the calling relay R' is cut off from line a' , b' as long as the subscribers are connected, thus preventing—besides other effects—that the calling of the subscriber No. 1523 does not further affect the group-switch, which would cause other preselectors to commence operation. Independently of the excitation of T', the connection of line c' to -F, or ground, in the preselector has the further effect that the subscriber's line a' , b' continues to be blocked after the blocking of c' over working contact r^1 , line 1', relay E, line 7', battery V, -F—which has been in effect till now—has been stopped. While the preselector in Fig. 7 remains set, the common apparatus has returned to its normal position in which it is ready to receive a new call.

2) *The Setting on Lines of the First and Second Selector (Figs. 8 and 9 and of the Connector (Fig. 10).*

5 The preselector being set on line as per Fig. 7, the calling subscriber is connected to +F over line a' , b' —contact-arm of the preselector—line a^0 , b^0 —lever e^1 , i^1 (stroked first position)—relay A^1 , B^1 —line 45, 44—resting contacts g^2 , g^3 . Thus the same condition is brought about as in the case of the Strowger system in its usual form. The only existing difference is in the fact that—between the calling subscriber and the first selector—there is not a lasting but only a 10 transitory connection as long as such is really wanted. This difference does not influence however the mechanical and electrical construction of the single selectors and connectors, the trunking between them, their grouping and placing; in short, the totality of equipments, from the first selectors to all further switching stages, corresponds with the usual well-known construction of the Strowger-system. Thus also all further operations are carried on after the practice of this system, so that the following description of this part can be abbreviated correspondingly.

30 a) *The Setting on Line of the First Selector, Fig. 8.*

This setting on line follows the first turning of the dial of the subscriber's telephone No. 1523 from finger hole 1, the impulse sending device in the subscriber's apparatus grounding once line a' and, thereafter, also grounding once line b' . Correspondingly, each of the relays A^1 and B^1 are also energized once.

Impulse over relay A^1 : +F, resting contact g^2 (Fig. 7), line 45, relay A^1 , lever e^1 , line a^0 , contact-arm of the preselector, subscriber's line a' , impulse sender in the subscriber's apparatus, ground, and back to -F.

Impulse over relay B^1 : +F, lever g^3 , line 44, relay B^1 , lever i^1 , line b^0 , contact-arm of the preselector, subscriber's line b' , impulse sender, ground, and back to -F.

50 Relay A^1 transfers the impulse received to the lifting magnet H^1 , lever a^1 closing a circuit +F, a^1 , s^1 , H^1 , -F. H^1 responds and lifts the contact-arm one step in front of the contacts of lines 11, 12, 13 . . .

55 Relay B^1 transfers the impulse received to the busy magnet S^1 , lever b^1 closing a circuit over +F, S^1 , b^1 , -F. Magnet S^1 attracts the lever s^1 and the busy escapement. The latter, when S^1 is made currentless, allows the levers e^1 , i^1 , o^1 , u^1 to go over from the stroked position to the middle position. At the same time u^1 inserts the turning magnet D^1 in the interrupter circuit +F, u^1 , D^1 , U, -F.

60 The contact-arm rotates under the effect of the impulses which the electromagnet D^1 receives from U. The lines connected to the contacts 11, 12 . . . 16—as has been presumed—being busy, the contact-arm turns in the well-known manner until it reaches the contact 17 of the line a^1 , b^1 , c^1 , at the same time completing, by cutting off the relays A^1 , B^1 as shown in the drawing, a direct connection from the calling subscriber to the second selector.

receives from U. The lines connected to the contacts 11, 12 . . . 16—as has been presumed—being busy, the contact-arm turns in the well-known manner until it reaches the contact 17 of the line a^1 , b^1 , c^1 , at the same time completing, by cutting off the relays A^1 , B^1 as shown in the drawing, a direct connection from the calling subscriber to the second selector.

b) *The Setting on Line of the Second Selector, Fig. 9.*

Then follows the second turning of the dial of the subscriber's apparatus No. 1523 from finger hole 5, the impulse sender of the telephone grounding a' five times and, following this, grounding b' once. Thus relay A^2 is grounded five times and relay B^2 once.

Impulses over relay A^2 : +F, relay A^2 , lever i^2 (stroked position), line a^1 , contact-arm of the first selector, lever e^1 , line a^0 , contact-arm of the preselector, subscriber's line a' , impulse sender, ground, and back to -F.

Impulse over B^2 : +F, B^2 , lever i^2 , line b^1 , contact-arm of the first selector, lever i^1 , line b^0 , contact-arm of the preselector, subscriber's line b' , impulse sender, ground, and back to -F. Relay A^2 transfers the five impulses to the lifting magnet H^2 and B^2 transfers its impulse to the busy magnet S^2 . The impulses flow on in a similar way as in the first selector (Fig. 8) the wiring of which is identical to that of Fig. 9 with the exception of the contact f^3 . The lifting magnet H^2 , by being energized five times, lifts the contact-arm to the height of the contacts of the lines 51, 52, 53 . . . S^2 being excited, the contact-arm then slides over the lines 51 to 56 presumed to be busy to the contact 57 of the line a^1 , b^1 , c^1 . Then the calling subscriber is connected to the connector of Fig. 10.

c) *The Setting on Line of the Connector, Fig. 10.*

This is attained by the third and fourth turning of the dial from 3 and 8. Correspondingly relay A^3 is energized three times by the first and eight times by the second turning of the dial, and, following each turning, relay B^3 is energized once.

Impulses over relay A^3 : +F, A^3 , line a^{11} , contact-arm of the second selector, lever e^2 , line a^1 , contact-arm of the first selector, lever e^1 , line a^0 , contact-arm of the preselector, subscriber's line a' , impulse sender, ground, and back to -F.

Impulse over relay B^3 : +F, B^3 , line b^{11} , contact-arm of the second selector, lever i^2 , line b^1 , contact-arm of the first selector, lever i^1 , line b^0 , contact-arm of the preselector, subscriber's line b' , impulse sender, ground, and back to -F.

The first three impulses over relay A^3 are transferred to the lifting magnet H^3 , the contact-arm being lifted up to the contact-row 31, 32 . . . shown in the drawing. Relay B^3

being excited once hereafter, this causes also the busy magnet S^3 to be energized, so as to make the levers e^3, i^3, o^3, u^3 go over from the stroked to the middle position, lever u^3 inserting the turning magnet D^3 in place of the lifting magnet H^3 . The following eight impulses over relay A^3 are transferred to the turning magnet D^3 , the contact-arm being rotated as far as the contacts 38 of the line a'', b'', c'' . The relay B^3 , being excited once hereafter, attracts its armature and thereby includes the busy magnet S^3 in a circuit $+F, S^3, b^3, -F$, whereupon the said busy magnet attracts its armature and includes itself in a circuit $+F, S^3, s^4, a^3, -F$, whereby S^3 remains energized and the levers e^3, i^3, o^3 and u^3 are retained in their middle positions. As soon as the calling subscriber by pressing down upon the ringer button d sends a new impulse over the relay A^3 , the circuit above named over S^3 is interrupted by a^3 , the quadruple lever switch is brought into the position shown in full lines and at once the ringer relay L is energized by a current over the circuit $+F, L, u^3, s^3, a^3, -F$. If the desired line is already busy, that is to say, if c'' is connected in another connector or preselector to $-F$, a circuit is closed over L while the levers e^3, i^3, o^3 and u^3 are in their middle positions, which closes the contact at lever b^3 , and thereby prevents the calling subscriber from interrupting the current over S^3 , thus making it impossible for such calling subscriber to cause the levers to pass to the extreme position shown in full lines in the drawing.

When the ringing relay responds, it connects line a'', b'' over the levers e^3, i^3 and b^3, l^3 to the alternate current generator C , Fig. 5. Thus alternate current is made to flow to the desired subscriber's telephone No. 1538, so that the bell rings as long and as often as the calling subscriber presses his button d . When the levers e^3, i^3, o^3, u^3 turn over to the third position, line c'' is connected to $-F$ or ground over the contact-arm and lever o^3 , and thus line a'', b'' is blocked for other subscribers. At the same time a constant current $-F$, lever o^3 , contact-arm of the connector, line c'' , resting contact of the relay R'' , cut-off relay T'' , lines 5' and 3', $+F$ commences to flow which energizes the cut-off relay T'' and thus cuts the calling relay R'' out of the line a'', b'' which prevents, when the called subscriber No. 1538 takes off his receiver, that a preselector is made to operate.

3) The Releasing of the Switches.

This is effected every time the calling subscriber hangs on his receiver, the downward-moving receiver arm of the telephone shortly grounding line a' and b' simultaneously. The relays A^3 and B^3 Fig. 10 are then—as described previously—energized simultaneously

and an impulse $+F, M^3$, lever b^4 and $a^3, -F$ 65 is closed, causing the releasing magnet M^3 to respond. The electromagnet M^3 transfers the impulse, by closing the contact at m^3 , to the releasing magnets M^2 , Fig. 9, M^1 , Fig. 8 and M , Fig. 7 of the other switches, so as to 70 energize, simultaneously, the releasing magnets of all four switches. Then each of the magnets causes the corresponding contact-arm and the quadruple lever-switch to return, in the well-known manner, to their normal positions, the blocking of all the lines $a', b'—a^1, b^1—a^1, b^1—a'', b''$ being suspended simultaneously, and also the cut-off relays T' and T'' ceasing to be energized. 75

C. Closing Remarks.

The described types of apparatus and the wiring diagrams serve particularly—as is expressly mentioned here—but for an explanation of the invention. Specially in place of 85 the well-known Strowger switches with contact-arms movable in the vertical as well as in the horizontal direction, any other automatic switching telephone system can be taken as equivalent. Also the described 90 method of the setting on line of the preselectors combined with the arrangement of a group-switch is, although a new feature and an essential improvement as compared to the methods hitherto known with reference to 95 simplicity and rapidity of operation but to be regarded as a special solution of the problem treated by the invention.

To illustrate the rapidity of operation of the selectors, it may be stated briefly that the time required for the setting on line No. 23 of the preselector, Fig. 7, described in section B' hereinbefore, is only 0.3 seconds reckoned from the taking up the receiver. The setting on line No. 00 which is the most unfavorable 100 possibility lasts one second.

When two or more subscribers send calls at the same time, the operation of the preselectors is not disturbed because the arm of the tens-finder and also the arm of the preselector start as hereinbefore described for a single call, but always stop at the first live contact which they reach. In consequence of this, the calling line having the lowest number is given the first choice of a preselector and then follow the others one after another.

Owing to the rapidity of operation, it will rarely happen that calls occur at the same time in a group and even when this does occur, there is no delay worthy of notice.

The fundamental and characteristic feature of the invention consists in the combination of the double cord principle with the well-known Strowger group arrangement by which is attained, as will be clear from Fig. 1 of the drawings, and according to the demands of the traffic, a uniform equipment of all kinds of switches, such as preselectors,

first and second selectors, and connectors which result has not been obtained hitherto by any other system.

By this invention, the total number of switches is reduced to a minimum never obtained heretofore, without the necessity of employing any further means except a calling and cut-off relay for each subscriber and a simple group switch.

10 Having thus fully described my invention, what I claim is:

1. In an automatic telephone system, the combination, with the subscribers' lines divided in groups, of a plurality of preselectors and first selectors for each line group, each preselector comprising line contacts connected to the subscribers' lines of the group, a traveling contact device and means for moving said contact device to cause it to make contact with the line contacts, each first selector comprising line contacts, a traveling contact device in electrical communication with the traveling contact device of one of the preselectors, and means for moving this traveling contact to its line contacts, trunk lines connected in multiple to the line contacts of the first selectors, an auxiliary switch common to a plurality of preselectors, coupled for a call with one of said preselectors and working simultaneously with the same, and means connected with the trunk lines and arranged to make the final connection over the selected trunk line to the desired subscriber.
2. In an automatic telephone system, the combination, with the subscribers' lines divided in groups, of a plurality of preselectors for each line group, each comprising line contacts connected in multiple to the respective subscribers' lines of the group, a traveling contact device and means for moving said contact device to cause it to make contact with the line contacts, a plurality of first selectors for each line group, each having line contacts, trunk lines divided in sets and connected in multiple to the line contacts of the first selectors, a traveling contact device for each first selector, the traveling contact device of each first selector being in electrical communication with the traveling contact device of one of the preselectors, an auxiliary switch common to a plurality of preselectors, coupled for a call with one of said preselectors and working simultaneously with the same, means for moving the traveling contact device of each first selector into engagement with the contacts of an unoccupied trunk line of the desired set, and means connected with the contacts of the first selectors and arranged to make the final connections to the desired subscriber.
3. In an automatic telephone system, the combination, with the subscribers' lines divided in groups, and for each line group a plurality of pairs of switches, each pair comprising a preselector and a first selector, each preselector and first selector comprising line contacts, a traveling contact device coating with the individual line contacts and means for moving the traveling contact device, the traveling contact device of each preselector being in electrical communication with the traveling contact device of its companion first selector, an auxiliary switch common to a plurality of preselectors, coupled for a call with one of said preselectors and working simultaneously with the same, the line contacts of the preselectors being connected to the respective subscribers' lines of the group, of trunk lines divided in sets and connected in multiple to the line contacts of the first selectors, and means arranged to make the final connection to the desired subscriber.

4. In an automatic telephone system, the combination, with the subscribers' lines divided in groups, of a plurality of pairs of switches for each line group, each pair comprising a preselector and a corresponding first selector, each preselector and first selector comprising line contacts, a traveling contact device and means for moving the traveling contact device into engagement with the single line contacts, the traveling contact device of each preselector being in electrical communication with that of its companion first selector, the line contacts of the preselectors being connected to the corresponding subscribers' lines, trunk lines connected to the line contacts of the first selectors, an auxiliary switch common to a plurality of preselectors, coupled for a call with one of said preselectors and working simultaneously with the same, a calling relay for each subscriber arranged to set in action said auxiliary switch and the means for moving the traveling contact device of an idle preselector, and means actuated at the calling station for operating the traveling contact device of the corresponding first selector.

5. In an automatic telephone system, the combination, with the subscribers' lines divided in groups, a plurality of preselectors and first selectors for each line group arranged in pairs, each preselector and first selector comprising line contacts, a traveling contact device and means for moving its traveling contact device, the traveling contact device of each preselector being in electrical communication with that of its corresponding first selector, the subscribers' lines of the group being connected to the line contacts of the preselectors, trunk lines connected to the line contacts of the first selectors, an auxiliary switch common to a plurality of preselectors, coupled for a call with one of said preselectors and working simultaneously with the same, a calling relay for each subscriber's line arranged to set in action said auxiliary switch and an idle preselector.

6. In an automatic telephone system, the combination, with the subscribers' lines divided in groups, a plurality of pairs of switches for each line group, each pair comprising a preselector and a first selector, each preselector and first selector comprising line contacts, a traveling contact device coating with the individual line contacts and means for moving the traveling contact device, the traveling contact device of each preselector being in electrical communication with the traveling contact device of its companion first selector, an auxiliary switch common to a plurality of preselectors, coupled for a call with one of said preselectors and working simultaneously with the same, a calling relay for each subscriber's line arranged to set in action said auxiliary switch and an idle preselector.

upon a call, means at the subscriber's stations to actuate automatically the corresponding calling relay when the receiver is taken up, and means at the subscribers' stations for operating and controlling the first selector and for making the final connection over the selected trunk line.

6. In an automatic telephone system, the combination, with the subscribers' lines divided in groups, of a plurality of pairs of switches for each line group, each pair comprising a preselector and corresponding first selector, each preselector and first selector comprising line contacts, a traveling contact device and means for moving the traveling contact device into engagement with the single line contacts, the traveling contact device of each preselector being in electrical communication with that of its companion first selector, the line contacts of the preselector being connected to the corresponding subscribers' lines, trunk lines connected to the line contacts of the first selectors, an auxiliary switch common to a plurality of preselectors, coupled for a call with one of said preselectors and working simultaneously with the same, a calling relay for each subscriber arranged to set in action said auxiliary switch and the means for moving the traveling contact device of an idle preselector, and to stop the said preselector upon the arrival of its traveling contact device at the contacts of the calling subscriber's line, and means at the calling station for controlling the traveling contact device of the corresponding first selector.

7. In an automatic telephone system, the combination, with the subscribers' lines divided in groups, of a plurality of pairs of switches for each line group, each pair comprising a preselector and a corresponding first selector, each preselector and first selector comprising line contacts, a traveling contact device and means for moving the traveling contact device into engagement with the single line contacts, the traveling contact device of each preselector being in electrical communication with that of its companion first selector, the line contacts of the preselectors being connected to the corresponding subscribers' lines, trunk lines connected to the line contacts of the first selectors, an auxiliary switch common to a plurality of preselectors, coupled for a call with one of said preselectors and working simultaneously with the same, a calling relay for each subscriber, a common calling relay arranged to be actuated by any subscriber's calling relay and to set in action said auxiliary switch and the means for moving the traveling contact device of an idle preselector, and means actuated at the calling station for operating the traveling contact device of the corresponding first selector.

8. In an automatic telephone system, the

combination, with the subscribers' lines divided in groups, of a plurality of switches for each line group, said switches being arranged in pairs, each pair comprising a preselector and a first selector, each preselector and its first selector comprising line contacts, a traveling contact device arranged to engage said line contacts, the traveling contact device of each preselector being in electrical communication with that of the corresponding first selector, the line contacts of each preselector being connected to the corresponding subscribers' lines, trunk lines connected to the line contacts of the first selectors, means for moving said traveling contact devices, an auxiliary switch common to a plurality of preselectors, coupled for a call with one of said preselectors and working simultaneously with the same, a calling relay for each subscriber arranged to set in action the means for moving the traveling contact device of a preselector, a cut-off relay for each subscriber arranged to cut out the calling subscriber's calling relay when the preselector is set on the calling line, means at the calling station for controlling the traveling contact device of the first selector, and means operated over the selected trunk line for making the final connection to the desired subscriber.

9. In an automatic telephone system, the combination, with the subscribers' lines divided in groups, of a plurality of switches for each line group, said switches being arranged in pairs, each pair comprising a preselector and a corresponding first selector, each preselector and its first selector comprising line contacts, a traveling contact device arranged to engage said line contacts, the traveling contact device of each preselector being in electrical communication with that of the corresponding first selector, the line contacts of each preselector being connected to the corresponding subscribers' lines, trunk lines connected to the line contacts of the first selectors, an auxiliary switch common to a plurality of preselectors, coupled for a call with one of said preselectors and working simultaneously with the same, means for moving said traveling contact devices, a calling relay for each subscriber arranged to set in action said auxiliary switch and the means for moving the traveling contact device of a preselector, a cut-off relay for each subscriber arranged to cut out the called subscriber's calling relay, means actuated at the calling station for controlling the traveling contact device of the first selector, and means operated over the selected trunk line for making the final connection to the desired subscriber.

10. In an automatic telephone system, the combination, with the subscribers' lines divided in groups, of a plurality of switches for each line group, said switches being arranged in pairs, each pair comprising a preselector

and a first selector, each preselector and its first selector comprising line contacts, a traveling contact device of each preselector being in electrical communication with that of the corresponding first selector, the line contacts of each preselector being connected to the corresponding subscribers' lines, trunk lines connected to the line contacts of the first selectors, means for moving said traveling contact devices, an auxiliary switch common to a plurality of preselectors, coupled for a call with one of said preselectors and working simultaneously with the same, and a pair of relays for each subscriber's line, each pair comprising a calling and a cut-off relay, the calling relay being arranged to set in action said auxiliary switch and an idle preselector upon a call, the cut-off relay being arranged to cut out its calling relay when the corresponding subscriber's line is occupied.

11. In an automatic telephone system, the combination, with the subscribers' lines, divided in groups, of a plurality of preselectors and first selectors for each line group, each comprising line contacts, a traveling contact device arranged to engage its line contacts, and means for moving the traveling contact device, the traveling contact device of each preselector being in electrical communication with that of one of the first selectors, the contacts of the preselectors being connected to the corresponding subscribers' lines, trunk lines connected in multiple to the first selectors, an auxiliary switch common to a plurality of preselectors, coupled for a call with one of said preselectors, and arranged to control its traveling contact device to bring the same as needed in engagement with the contacts of a calling line, means actuated at the calling station for moving the traveling contact device of the first selector and for making the final connection over the selected trunk line to the desired subscriber.

12. In an automatic telephone system, the combination, with the subscribers' lines divided in groups, of a plurality of preselectors and first selectors for each line group, each comprising line contacts, a traveling contact device arranged to engage its line contacts, and means for moving the traveling contact device, the traveling contact device of each preselector being in electrical communication with that of one of the first selectors, the contacts of the preselectors being connected to the corresponding subscribers' lines, trunk lines connected in multiple to the first selectors, an auxiliary switch common to a plurality of preselectors, coupled for a call with one of said preselectors, and arranged to drive its traveling contact device to the contacts of the calling subscriber's line, a coupling device for each preselector to bring its means for moving the traveling contact device in communication with said auxiliary switch ready for a call,

and means actuated at the calling station for moving the traveling contact device of the first selector and for making the final connection over the selected trunk line to the desired subscriber.

13. In an automatic telephone system, the combination, with the subscribers' lines divided in groups, of a plurality of preselectors and first selectors for each line group, each comprising line contacts, a traveling contact device arranged to engage its line contacts, and means for moving the traveling contact device, the traveling contact device of each preselector being in electrical communication with that of one of the first selectors, the contacts of the preselectors being connected to the corresponding subscribers' lines, trunk lines connected in multiple to the first selectors, an auxiliary switch common to a plurality of preselectors, coupled for a call with one of said preselectors and arranged to drive its traveling contact device to the contacts of the calling subscribers line, a preselector finder controlled by the preselectors and arranged to couple an idle preselector for the next call with said auxiliary switch, means actuated at the calling station for moving the traveling contact device of the first selector, and means operated over said trunk lines for making the final connection between subscribers' lines.

14. In an automatic telephone system, the combination, with the subscribers' lines divided in groups and in sub-groups, and, for each line group local circuits equal in number to the number of the sub-groups; for each line group a plurality of preselectors, each comprising subscribers' line contacts arranged in series corresponding to the sub-groups, a traveling contact device and means for moving the traveling contact device to the series of contacts and along these, a calling relay in each subscriber's line arranged to set in action an idle preselector upon a call and to alter the condition of the local circuit of the sub-group to which its line belongs; for each line group a common auxiliary switch coupled with an idle preselector ready for a call and working synchronously with the preselector and arranged to stop the traveling contact device of the preselector at the series of contacts of the calling subscriber's sub-group and for causing said traveling contact device to come over the contacts of the calling subscriber's line.

15. In an automatic telephone system, the combination, with subscribers' lines divided in groups and sub-groups, and, for each line group, local circuits equal in number to the sub-groups; for each line group a plurality of preselectors, each comprising subscribers' line contacts arranged in rows corresponding to the sub-groups, a traveling contact device and means for moving said traveling contact device to a desired row and along such

row, a calling relay in each subscriber's line arranged to set in action an idle preselector upon a call and to close the local circuit of the sub-group to which its line belongs; for 5 each line group a common auxiliary switch coupled for a call and working in synchronism with an idle preselector, the auxiliary switch having contact points for the said local circuits, a traveling contact device 10 acting with the contact points, and a relay device arranged to be connected successively to the single local circuits to find the calling subscriber's sub-group; to stop the traveling contact device of the companion preselector 15 at the corresponding contact row, and to cause the preselector to start over the single contacts of the row.

16. In an automatic telephone system, the combination, with the subscribers' lines divided in groups, of a plurality of pairs of switches for each line group, each pair comprising a preselector and a first selector, each preselector and its corresponding first selector comprising line contacts, a traveling contact 20 device coacting with its line contacts and means for moving said traveling contact devices, the traveling contact device of each preselector being in electrical communication with that of the companion first selector, 25 the contacts of the preselectors being connected to the corresponding subscribers' lines of the group, trunk lines connected to the line contacts of the first selectors, an auxiliary switch common to a plurality of preselectors, coupled for a call with one of said 30 preselectors, and working simultaneously with the same, a central battery for energizing the means for moving the traveling contacts of the preselectors, an interrupter device 35 for the automatic working of the preselectors, means for controlling the interrupter device to set the traveling contact of an idle preselector on a calling subscriber's line, means at the subscribers' stations for starting an idle preselector and for actuating and 40 controlling its corresponding first selector, and means connected with the trunk lines and arranged to make the final connection to the desired subscriber.

50 17. In an automatic telephone system, the combination, with the subscribers' lines divided in groups, a plurality of preselectors and selectors arranged in pairs, and a plurality of connectors for each line group, each 55 preselector, selector and connector comprising line contacts, a traveling contact device and means for moving its traveling contact device into engagement with its line contacts, the traveling contact device of each 60 preselector being in electric communication with the traveling contact of its corresponding selector, an auxiliary switch common to a plurality of preselectors, coupled for a call with one of said preselectors, and working 65 simultaneously with the same, the sub-

scribers' lines of the group being connected in multiple as incoming lines to the line contacts of the preselectors and as outgoing lines to the line contacts of the connectors, a system of trunk lines divided in sets and each 70 connected in multiple to the respective line contacts of the selectors and to the traveling contact device of a corresponding connector, means for the automatic working of the preselectors to set the traveling contact device 75 of an idle preselector on a calling line, and means at the subscribers' stations to start an idle preselector and for actuating and controlling its corresponding selector and a connector of the desired subscriber's line group. 80

18. In an automatic telephone system, the combination, with the subscribers' lines divided in groups, a plurality of preselectors and first selectors arranged in pairs, a plurality of connectors, and a plurality of intermediate selectors for each line group, each preselector, first selector, intermediate selector and connector comprising line contacts, a traveling contact device and means for moving its traveling contact device in engagement with its line contacts, the traveling contact device of each preselector being in electric communication with the traveling contact device of its corresponding first selector, 90 an auxiliary switch common to a plurality of preselectors, coupled for a call with one of said preselectors, and working simultaneously with the same, systems of trunk lines, one system for each plurality of selectors, the trunk lines of each system being divided in 100 sets and each trunk line connected in multiple to the respective contacts of its corresponding selectors and to the traveling contact device of a succeeding selector or connector, the subscribers' lines of the group being connected in multiple as incoming lines to the line contacts of the preselectors and as outgoing lines to the line contacts of the connectors, means for the automatic working of the preselectors to set the traveling contact 110 of an idle preselector on a calling line; and means at the subscribers' stations to start an idle preselector and for actuating and controlling its first selector, the selected intermediate selectors, and a connector of the desired subscriber's line group. 115

19. In an automatic telephone system, the combination, with the subscribers' lines divided in groups, of a plurality of double switches, each consisting of a preselector and a selector, and a plurality of single switches, each consisting of a connector, for each line group, each preselector, selector and connector comprising line contacts, a traveling contact device and means for moving its 120 traveling contact device into engagement with its line contacts, the traveling contact device of each preselector being in electric communication with the traveling contact of its corresponding selector, an auxiliary switch 125

- common to a plurality of preselectors, coupled for a call with one of said preselectors, and working simultaneously with the same, the subscribers' lines of the groups connected 5 in multiple as incoming lines to the line contacts of the preselectors, and as outgoing lines to the line contacts of the connectors, and a system of trunk lines divided in sets and each connected in multiple to the respective line contacts of the selectors and to the traveling contact device of a corresponding connector, the double switches being arranged to make connections from a calling subscriber's line to an unoccupied trunk line 15 of the desired subscriber's line group, each of the single switches being arranged to make connections from its incoming trunk line to a desired subscriber's line.
20. In an automatic telephone system, the combination, with the subscribers' lines divided in groups, a plurality of double switches, each double switch consisting of a preselector and a first selector, and a plurality of single switches, part consisting of connectors and 25 part of intermediate selectors, each preselector, first selector, intermediate selector, and connector comprising line contacts, a traveling contact device and means for moving its traveling contact device in engagement with its line contacts, the traveling contact device of each preselector being in electric communication with the traveling contact device of its corresponding first selector, an auxiliary switch common to a plurality of 30 preselectors, coupled for a call with one of said preselectors, and working simultaneously with the same, systems of trunk lines, one system for each plurality of selectors, the trunk lines of each system being divided in 35 sets and each trunk line connected in multiple to the respective contacts of its corresponding selectors and to the traveling contact device of a succeeding selector or connector, the subscribers' lines of the group be-

ing connected in multiple as incoming lines 45 to the line contacts of the preselectors and as outgoing lines to the line contacts of the connectors, the double switches being arranged to make connection from a calling subscriber's line to an unoccupied first trunk line of the 50 desired set, the single switches being arranged to continue the connection from trunk line to trunk line and finally to the desired subscriber's line.

21. In an automatic telephone system, the combination, with the subscribers' lines divided in groups, of a plurality of preselectors and first selectors for each line group, each comprising line contacts, a traveling contact device arranged to engage its line contacts, 60 and means for moving the traveling contact device, the traveling contact device of each preselector being in electrical communication with that of one of the first selectors, the contacts of the preselectors being connected to 65 the corresponding subscribers' lines, trunk lines connected in multiple to the first selectors, an auxiliary switch common to a plurality of preselectors, coupled for a call with one of said preselectors and arranged to drive 70 its traveling contact device to the contacts of the calling subscriber's line, switching apparatus controlled by the preselectors and arranged to bring the next idle preselector into the sphere of control of the said auxiliary switch, means actuated at the calling station for moving the traveling contact device of the first selector, and means operated over 75 said trunk lines for making the final connection between subscribers' lines.

In testimony whereof I have signed my name to this specification in the presence of two subscribing witnesses.

FRIEDRICH MERK.
